UNITED STATES PATENT OFFICE

164,208

AUTOMOBILE

Millard H. Toncray and Frank S. Spring, Grosse Pointe, Mich., assignors to Hudson Motor Car Company, Detroit, Mich., a corporation of Michigan

Application February 20, 1948, Serial No. 144,643

Term of patent 14 years

(Cl. D14—3)

To all whom it may concern:

Be it known that we, Millard H. Toncray and Frank S. Spring, citizens of the United States, residing at Grosse Pointe, county of Wayne, State of Michigan, have invented a new, original, and ornamental Design for an Automobile, of which the following is a specification, reference being had therein to the accompanying drawings, forming a part thereof, in which

Fig. 1 is a side elevation of an automobile illustrating our new design.

Fig. 2 is a vertical sectional view taken substantially along line 2—2 of Fig. 1 and illustrates a contour of the side of the body in accordance with our new design.

Figs. 3, 4, 5 and 6 are vertical sectional views taken substantially along lines 3—3, 4—4, 5—5 and 6—6, respectively, of Fig. 1 looking in the direction of the arrows, these views being on a scale based substantially on the actual size of the automobile and on larger scales than Fig. 2.

Fig. 7 is a perspective view of the automobile illustrated in Fig. 1.

The dominant features of our new design reside in the portions shown in full lines. The opposite side of the body is the same as that shown in Fig. 1.

We claim:

The ornamental design for an automobile, substantially as shown and described.

MILLARD H. TONCRAY.
FRANK S. SPRING.
